UNITED STATES PATENT OFFICE

170,335

SEWING MACHINE FRAME

Malcolm S. Park, Mount Kisco, N. Y., assignor to
The Singer Manufacturing Company, Elizabeth,
N. J., a corporation of New Jersey

Application October 15, 1952, Serial No. 21,832

Term of patent 14 years

(Cl. D70—1)

To all whom it may concern:

Be it known that I, Malcolm S. Park, a citizen of the United States, residing at Mount Kisco, in the county of Westchester and State of New York, have invented a new, original, and ornamental Design for a Sewing Machine Frame, of which the following is a specification, reference being had to the accompanying drawings, forming a part thereof.

Fig. 1 is a perspective view of a sewing machine frame, looking toward the left front corner, showing my new design.

Fig. 2 is a perspective view looking toward the right rear corner of the frame illustrated in Fig. 1.

The dominant features of my design reside in those portions shown in full lines.

I claim:

The ornamental design for a sewing machine frame, substantially as shown and described.

MALCOLM S. PARK.
